(57) **CLAIM**

The ornamental design for a magazine for a firearm, as shown and described.

DESCRIPTION

FIG. 1 is a left, bottom, front perspective view of a magazine for a firearm showing our new design;
FIG. 2 is a right side elevation view of the magazine for a firearm of FIG. 1;
FIG. 3 is a left side elevation view of the magazine for a firearm of FIG. 1;
FIG. 4 is a top plan view of the magazine for a firearm of FIG. 1;
FIG. 5 is a bottom plan view of the magazine for a firearm of FIG. 1;
FIG. 6 is a front elevation view of the magazine for a firearm of FIG. 1;
FIG. 7 is a rear elevation view of the magazine for a firearm of FIG. 1; and,
FIG. 8 is a right, rear perspective view of the magazine for a firearm of FIG. 1.
The broken lines showing portions of the design in all figures are included for the purpose of illustrating environment and unclaimed features and form no part of the claimed design.

1 Claim, 6 Drawing Sheets
